ABSTRACT OF THE DISCLOSURE

An electrographic apparatus for depositing upon a charge retentive medium a latent image of controllable size and shape produced by ions discharged from coaxially arranged electrodes; the shape and size of said image is dependent upon an electrical bias on a control electrode in the ion path and the physical shape and size of an aperture opening in the control electrode and the thickness of the control electrode.

This invention relates to apparatus for depositing a charged image on a recording medium, and more particularly to an electrographic print station for depositing a charged image of controllable magnitude upon a charge-retentive medium.

In copending application S.N. 729,847, filed Apr. 21, 1958, now U.S. Patent No. 3,195,142, entitled, "Electrographic Recording Process and Apparatus," by Robert E. Benn and Richard S. Sakurai, which patent is assigned to the assignee of this application, an improved apparatus for depositing a charge on a recording medium is described. A print head is provided having a 5 x 7 matrix of pin-shaped print electrodes. A closely spaced initiating electrode, also pin-shaped, is provided for each of the print electrodes. The print head has a planar print face in which the print and initiating electrodes terminate. A planar back electrode is located at a distance from and substantially parallel to the print face.

Means are provided to apply a print voltage pulse to a print electrode. The print pulse establishes a unidirectional divergent electric field between the print electrode and the back electrode. While the intensity of this field is of sufficient value to sustain ionization within the gap between print and back electrodes, once electrically charged particles have been introduced into that gap, the field is insufficient to cause the initiation of such particles.

Such particles are introduced into the gap by an initiating pulse applied to the initiating electrode associated with the energized print electrode. Simultaneous application of a print pulse and an initiating pulse to associated initiating and print electrodes causes a disruptive discharge to occur between those electrodes.

The discharge introduces a large number of charged particles into the gap. The unidirectional electric field, which exists between the print electrode and back electrode, causes propagation of a stream of charged particles across the gap and the establishment of a charged area on the surface of a record medium located between the back electrode and the print head print face.

An advantage of the above system over previous techniques, wherein only a single electrode was used in the print head for both initiating and maintaining a discharge, is that since the voltage necessary to maintain discharge is less than that required to initiate one, the voltage that is required to be maintained between the print electrode and the back electrode is considerably lower where an initiating electrode is employed.

In certain applications, it is desirable to have control

2

over the size of the charged spot deposited on the recording medium. This has been possible with the print heads just described by varying parameters such as the gap between the record medium and the print face of the print head. However, this parameter may not be readily variable in operation.

Accordingly, it is an object of this invention to provide an improved electrographic print head.

It is another object of this invention to provide an electrographic print station wherein the magnitude of an individual charged area may be readily controlled.

It is a further object of this invention to provide an electrographic print station wherein the magnitude of a charged image may be altered over a wide range by the adjustment of a bias voltage.

A still further object of this invention is to provide an electrographic printing station incorporating a printing head and comprising a segmented control grid capable of modifying the field followed by a stream of ions to readily provide required shapes and sizes of charged indicia symbols created by depositing the stream of ions upon a recording medium.

These and other objects are achieved by the addition of an apertured control electrode to a print station of the type having a print head with one or more electrodes terminating at its face. Each print head electrode set is preferably coaxial, the central pin serving as an initiating electrode, the outer cylinder serving as a print electrode. An ion stream, established between a print head electrode and a back electrode, located behind the recording medium, passes through an aperture in the control electrode. A control voltage is applied to the control electrode. The shape of the ion stream and the size of the charged spot it creates upon the record medium may be readily controlled by manipulating the electrostatic field in the aperture through adjustment of the control voltage.

While some of the objects and a brief description of the invention have been given above, the invention and its objects will be best understood by referring to the following detailed descriptions and to the accompanying drawings wherein:

FIG. 1 is an isometric view, partially broken away, of a preferred embodiment of a print station incorporating the control electrode.

FIG. 2 is a cross section of FIG. 1 taken along the lines 2—2 and showing, in addition, in block and schematic form, the arrangement of voltage supplying circuits and sources used to operate the print station.

FIG. 3 is a graph of spot size as a function of control voltage.

FIG. 4 is a fragmentary pictorial and schematic plan view of another embodiment of the invention employing a segmented control electrode.

Referring to FIG. 1, there is shown print head 11 having a substantially planar print face 13 and an array of print head electrode sets 15 terminating in the print face. Resting next to the print face 13 is control electrode 17. The control electrode is of conductive or semiconductive material and has an array of apertures 18 corresponding to the print head electrode sets 15 in the head. The apertures are concentric with the print head electrode sets 15. A planar, back electrode 19 is located in a spaced-apart relationship with the control electrode and substantially parallel to it. Record medium 21 is located between the control electrode 17 and the back electrode 19.

FIG. 2 illustrates the arrangement in more detail. Each print head electrode set 15, embedded in the print head 11, is coaxial and comprises a central pin 23 which functions as the initiating electrode, and a cylindrical electrode 25 which functions as a print electrode. The initiating,

control, and back electrodes 17, 19, and 25 are connected to a power source 27. The control electrode 17 is connected to a variable voltage source 29 which is connected to a potentiometer 31. The initiating electrode 23 is connected to a variable voltage source 33 which is connected to a potentiometer 35. The back electrode 19 is connected to a variable voltage source 37 which is connected to a potentiometer 39. The power source 27 is connected to a power source 41 which is connected to a power source 43. The power source 41 is connected to a power source 45 which is connected to a power source 47. The power source 47 is connected to a power source 49 which is connected to a power source 51. The power source 51 is connected to a power source 53 which is connected to a power source 55. The power source 55 is connected to a power source 57 which is connected to a power source 59. The power source 59 is connected to a power source 61 which is connected to a power source 63. The power source 63 is connected to a power source 65 which is connected to a power source 67. The power source 67 is connected to a power source 69 which is connected to a power source 71. The power source 71 is connected to a power source 73 which is connected to a power source 75. The power source 75 is connected to a power source 77 which is connected to a power source 79. The power source 79 is connected to a power source 81 which is connected to a power source 83. The power source 83 is connected to a power source 85 which is connected to a power source 87. The power source 87 is connected to a power source 89 which is connected to a power source 91. The power source 91 is connected to a power source 93 which is connected to a power source 95. The power source 95 is connected to a power source 97 which is connected to a power source 99. The power source 99 is connected to a power source 101 which is connected to a power source 103. The power source 103 is connected to a power source 105 which is connected to a power source 107. The power source 107 is connected to a power source 109 which is connected to a power source 111. The power source 111 is connected to a power source 113 which is connected to a power source 115. The power source 115 is connected to a power source 117 which is connected to a power source 119. The power source 119 is connected to a power source 121 which is connected to a power source 123. The power source 123 is connected to a power source 125 which is connected to a power source 127. The power source 127 is connected to a power source 129 which is connected to a power source 131. The power source 131 is connected to a power source 133 which is connected to a power source 135. The power source 135 is connected to a power source 137 which is connected to a power source 139. The power source 139 is connected to a power source 141 which is connected to a power source 143. The power source 143 is connected to a power source 145 which is connected to a power source 147. The power source 147 is connected to a power source 149 which is connected to a power source 151. The power source 151 is connected to a power source 153 which is connected to a power source 155. The power source 155 is connected to a power source 157 which is connected to a power source 159. The power source 159 is connected to a power source 161 which is connected to a power source 163. The power source 163 is connected to a power source 165 which is connected to a power source 167. The power source 167 is connected to a power source 169 which is connected to a power source 171. The power source 171 is connected to a power source 173 which is connected to a power source 175. The power source 175 is connected to a power source 177 which is connected to a power source 179. The power source 179 is connected to a power source 181 which is connected to a power source 183. The power source 183 is connected to a power source 185 which is connected to a power source 187. The power source 187 is connected to a power source 189 which is connected to a power source 191. The power source 191 is connected to a power source 193 which is connected to a power source 195. The power source 195 is connected to a power source 197 which is connected to a power source 199. The power source 199 is connected to a power source 201 which is connected to a power source 203. The power source 203 is connected to a power source 205 which is connected to a power source 207. The power source 207 is connected to a power source 209 which is connected to a power source 211. The power source 211 is connected to a power source 213 which is connected to a power source 215. The power source 215 is connected to a power source 217 which is connected to a power source 219. The power source 219 is connected to a power source 221 which is connected to a power source 223. The power source 223 is connected to a power source 225 which is connected to a power source 227. The power source 227 is connected to a power source 229 which is connected to a power source 231. The power source 231 is connected to a power source 233 which is connected to a power source 235. The power source 235 is connected to a power source 237 which is connected to a power source 239. The power source 239 is connected to a power source 241 which is connected to a power source 243. The power source 243 is connected to a power source 245 which is connected to a power source 247. The power source 247 is connected to a power source 249 which is connected to a power source 251. The power source 251 is connected to a power source 253 which is connected to a power source 255. The power source 255 is connected to a power source 257 which is connected to a power source 259. The power source 259 is connected to a power source 261 which is connected to a power source 263. The power source 263 is connected to a power source 265 which is connected to a power source 267. The power source 267 is connected to a power source 269 which is connected to a power source 271. The power source 271 is connected to a power source 273 which is connected to a power source 275. The power source 275 is connected to a power source 277 which is connected to a power source 279. The power source 279 is connected to a power source 281 which is connected to a power source 283. The power source 283 is connected to a power source 285 which is connected to a power source 287. The power source 287 is connected to a power source 289 which is connected to a power source 291. The power source 291 is connected to a power source 293 which is connected to a power source 295. The power source 295 is connected to a power source 297 which is connected to a power source 299. The power source 299 is connected to a power source 301 which is connected to a power source 303. The power source 303 is connected to a power source 305 which is connected to a power source 307. The power source 307 is connected to a power source 309 which is connected to a power source 311. The power source 311 is connected to a power source 313 which is connected to a power source 315. The power source 315 is connected to a power source 317 which is connected to a power source 319. The power source 319 is connected to a power source 321 which is connected to a power source 323. The power source 323 is connected to a power source 325 which is connected to a power source 327. The power source 327 is connected to a power source 329 which is connected to a power source 331. The power source 331 is connected to a power source 333 which is connected to a power source 335. The power source 335 is connected to a power source 337 which is connected to a power source 339. The power source 339 is connected to a power source 341 which is connected to a power source 343. The power source 343 is connected to a power source 345 which is connected to a power source 347. The power source 347 is connected to a power source 349 which is connected to a power source 351. The power source 351 is connected to a power source 353 which is connected to a power source 355. The power source 355 is connected to a power source 357 which is connected to a power source 359. The power source 359 is connected to a power source 361 which is connected to a power source 363. The power source 363 is connected to a power source 365 which is connected to a power source 367. The power source 367 is connected to a power source 369 which is connected to a power source 371. The power source 371 is connected to a power source 373 which is connected to a power source 375. The power source 375 is connected to a power source 377 which is connected to a power source 379. The power source 379 is connected to a power source 381 which is connected to a power source 383. The power source 383 is connected to a power source 385 which is connected to a power source 387. The power source 387 is connected to a power source 389 which is connected to a power source 391. The power source 391 is connected to a power source 393 which is connected to a power source 395. The power source 395 is connected to a power source 397 which is connected to a power source 399. The power source 399 is connected to a power source 401 which is connected to a power source 403. The power source 403 is connected to a power source 405 which is connected to a power source 407. The power source 407 is connected to a power source 409 which is connected to a power source 411. The power source 411 is connected to a power source 413 which is connected to a power source 415. The power source 415 is connected to a power source 417 which is connected to a power source 419. The power source 419 is connected to a power source 421 which is connected to a power source 423. The power source 423 is connected to a power source 425 which is connected to a power source 427. The power source 427 is connected to a power source 429 which is connected to a power source 431. The power source 431 is connected to a power source 433 which is connected to a power source 435. The power source 435 is connected to a power source 437 which is connected to a power source 439. The power source 1143 is connected to a power source 1145 which is connected to a power source 1147. The power source 1147 is connected to a power source 1149 which is connected to a power source 1151. The power source 1151 is connected to a power source 1153 which is connected to a power source 1155. The power source 1155 is connected to a power source 1157 which is connected to a power source 1159. The power source 1159 is connected to a power source 1161 which is connected to a power source 1163. The power source 1163 is connected to a power source 1165 which is connected to a power source 1167. The power source 1167 is connected to a power source 1169 which is connected to a power source 1171. The power source 1171 is connected to a power source 1173 which is connected to a power source 1175. The power source 1175 is connected to a power source 1177 which is connected to a power source 1179. The power source 1179 is connected to a power source 1181 which is connected to a power source 1183. The power source 1183 is connected to a power source 1185 which is connected to a power source 1187. The power source 1187 is connected to a power source 1189 which is connected to a power source 1191. The power source 1191 is connected to a power source 1193 which is connected to a power source 1195. The power source 1195 is connected to a power source 1197 which is connected to a power source 1199. The power source 1199 is connected to a power source 1201 which is connected to a power source 1203. The power source 1203 is connected to a power source 1205 which is connected to a power source 1207. The power source 1207 is connected to a power source 1209 which is connected to a power source 1211. The power source 1211 is connected to a power source 1213 which is connected to a power source 1215. The power source 1215 is connected to a power source 1217 which is connected to a power source 1219. The power source 1219 is connected to a power source 1221 which is connected to a power source 1223. The power source 1223 is connected to a power source 1225 which is connected to a

central electrode 23 is separated from the print electrode 25 by insulating layer 27.

Back electrode 19 is tied to some reference potential, which may be electrical ground. Print electrode 25 is maintained at potential V_P by print voltage source 29. Initiating electrode 23 is connected through resistor 31 and secondary winding 33 of transformer 35 to print voltage source 29. The primary winding 37 of transformer 35 is connected to initiating pulse source 39.

Upon energization of initiating pulse source 39, initiating voltage pulse V_I appears across initiating electrode 23 and print electrode 25. This voltage is of a sufficient magnitude to cause a disruptive discharge 41 to occur between the electrodes 23 and 25. Resistor 31 is primarily a current-limiting resistor. Depending upon the polarity of the print voltage V_P , positive or negative ions in the form of a stream 43 are propagated toward the recording medium 21, depositing a charged spot 45 on it.

Control voltage V_C is applied to control electrode 17 by control voltage source 47. The control voltage V_C may be of the same polarity as the ions in the stream 43, in which event, the electrostatic field created within the aperture 18 by the control voltage V_C will have a constricting effect on the ion stream, tending to reduce spot size G. Conversely, the control voltage V_C may differ in polarity from that of ions in the ion stream 43, in which event, the electrostatic field within the aperture 18 will tend to enlarge the crosssectional size of the stream 43. When the ions in the stream and the control voltage V_C have opposite polarities, an increase in the control voltage will result in an increase in the size G of the charged spot 45.

While in no wise to be construed as limiting the scope of this invention to such values of parameters, the following figures are those used in a model which was built to incorporate the features shown in FIG. 2.

Initiating pin diameter A	-----	mils	5
Spark gap B	-----	do	3
Control electrode aperture diameter D	-----	do	50
Control electrode thickness E	-----	do	30
Control electrode-to-print medium spacing F	-----	do	20
Spot diameter G	-----	do	0 to 75
Print voltage V_P	-----	volts	-1,000
Control voltage V_C	-----	do	-500 to -1,500
Initiating voltage V_I	-----	do	-1,300
Resistor 31	-----	ohms	300K
Duration of voltage V_I	-----	microsec	40

The spot size G resulting from the above paramters may best be observed by referring to FIG. 3 wherein spot size G is plotted against control voltage V_C for three different control electrode thicknesses E. It may be seen that spot diameter G is an almost linear function of control voltage V_C with an increasing control voltage resulting in diminished spot size. This occurs since the greater the negative control voltage V_C , the larger the constricting effect it has upon the ion stream 43 passing therethrough.

Similarly, it may be observed that for a given control voltage V_C , spot size G may be diminished by increasing the control electrode thickness E. This follows, since, with a thicker electrode, constriction or expansion, in accordance with polarity of the control voltage, of the ion stream 43 is effected over a longer portion of the total path of the ion stream 43 to the recording medium.

Similarly, dimensions other than the control electrode thickness E may also be changed. Control electrode aperture diameter D, for example, may be reduced where a smaller range of spot diameters G is desired. Control electrode-to-print medium spacing F is noncritical, and may be changed without altering operation of the print head.

While in the illustration given above, the apertures 18 used were shown to be circular, this need not necessarily be so; for example, where a large number of closely spaced electrode pins are used in the print head, a row of such electrodes may have a common, slot-shaped aperture rather than individual circular apertures in the control

electrode where elliptical-shaped spots are desirable. Likewise, the electrode 17 need not be a single plate, but may be individual to each pin, and may be an integral part of the head itself.

Referring to FIG. 4, an embodiment is provided which affords greater flexibility and control over the shapes of the areas of charge deposited on the record medium. In this embodiment, the control electrode 17' is divided into segments 60. Four segments are shown in each section or group (not numbered) of control electrode 17' but more or less than four segments, and in various configurations, could be employed. The segments 60 are electrically insulated from each other by air pockets or electrical insulation 61. Where semiconductive material is used for the control electrode, junctions could be formed to provide the required insulating barriers between segments.

Individual sources of voltages, shown as V_{C1} , V_{C2} , V_{C3} , V_{C4} and V_{C5} , V_{C6} , V_{C7} , V_{C8} , are electrically connected to the segments 60 of the sections of control electrode 17'. Thus, different voltages may be applied to each segment 60. Additionally, corresponding segments 60 of each section of control electrode 17' may be connected to a common voltage source; for example, a left segment of each section might be connected to source B_{C1} , and a right segment of each section might be connected to source B_{C2} . Alternatively, some of the segments 60 may be grounded or may be left floating.

Voltage sources may be switched to different segments 60 for varying the combination of voltages applied to the segments 60.

Varying the voltages applied to the control electrode segments 60 varies the configuration of the electrostatic field around the ion beam and hence, migration of the ions to the recording medium is correspondingly affected so as to provide the desired shape and size of the discharges of ions upon the recording medium.

The use of the control electrode described above need not be confined to print stations employing a coaxial pin type print head. To the contrary, such an electrode may also be employed with the double pin arrangement described in the Benn-Sakurai patent previously referred to. Additionally, the control electrode may also be employed with the pin-bar arrangement disclosed in U.S. Patent No. 3,068,479, of Robert E. Benn, Richard S. Howell, and Richard S. Sakurai, entitled Electrographic Recording Apparatus and assigned to the assignee of this application. In both cases, the apertures of the control electrode will be located opposite the point in the print face where the ion stream originates. In the case of the Benn-Sakurai application, this may be some point intermediate the pair of initiating and print electrodes. In case of the Patent No. 3,068,479, this point may be between the initiating pin electrode and its associated print bar electrode.

Obviously many modifications and variations of the present invention are possible in the light of the above teachings. It is therefore to be understood that within the scope of the appended claims the invention may be practiced other than as specifically described and illustrated.

What is claimed is:

1. In an electrographic print head having coaxially arranged electrodes for depositing upon a record medium supported by a back electrode connected to a reference potential a charged image by means of an ion stream between said print head and said back electrode, the improvement comprising in combination, a control electrode substantially surrounding said ion stream and comprising segments arranged to form an aperture through which said ion stream passes, said segments being of a particular thickness and relatively electrically insulated from one another, means for applying individual voltage bias to each of said segments for controlling the size and shape of said charged image and

means for individually varying the electrical bias of each of said segments.

2. An electrographic print head having a substantially planar print face and an array of sets of coaxial electrodes terminating at said face for depositing charged images upon a record medium resting upon a grounded electrode, comprising:

means for generating and, in cooperation with said grounded electrode, for propelling ion streams to impinge upon said record medium;

a control electrode comprising groups of segments of selectable thicknesses, each group arranged to form an aperture through which one of said ion streams passes and each group substantially concentric with one of the sets of coaxial electrodes, and

means for biasing said segments at selected voltages in combination with the selected thickness of the segments of the control electrode, for affecting substantially linearly the shape and size of said charged images.
